(57) **CLAIM**

I claim the ornamental design for an enteral feeding pump accessory bag and carrying case, as shown and described.

DESCRIPTION

FIG. 1 is a front right perspective view of the enteral feeding pump accessory bag;

FIG. 2 is a front elevation view thereof;

FIG. 3 is a left side elevation view thereof;

FIG. 4 is a top plan view thereof;

FIG. 5 is a front right perspective view of the enteral feed bag carrying case, a flap thereof shown in a folded position;

FIG. 6 is a front elevation view thereof, the flap being raised;

FIG. 7 is a left side elevation view thereof with the flap raised;

FIG. 8 is a top plan view thereof with the flap raised;

FIG. 9 is a bottom view thereof with the flap raised;

FIG. 10 is a rear elevation view thereof with the flap raised; and,

FIG. 11 is a front elevation view of the enteral feeding pump accessory bag and the enteral feed bag carrying case, shown in operative arrangement.

The broken lines are shown for environmental purposes and form no part of the claimed design.
